UNITED STATES PATENT OFFICE.

FELIX BROWN, OF NEW YORK, N. Y.

DESIGN FOR A PILLOW-BLOCK.

SPECIFICATION forming part of Design No. 14,138, dated July 31, 1883.

Application filed June 11, 1883. Term of patent 7 years.

To all whom it may concern:

Be it known that I, FELIX BROWN, a citizen of the United States, residing at New York, in the county and State of New York, have invented and produced a new and original Design for Pillow-Blocks, of which the following is a specification, reference being had to the accompanying drawings.

This design consists in a frame having an arched top and straight sides provided with longitudinal moldings on the outer edges, combined with transverse moldings which intersect the longitudinal moldings at the junctions of said top and sides.

15 In the accompanying drawings, Figure 1 represents a side view; and Fig. 2, a horizontal section on the line x x , Fig. 1, looking upward.

Similar letters indicate corresponding parts.

The letter A designates the arched top of the frame, and B the straight sides thereof, the latter rising from a base, C. The letter D indicates a longitudinal molding on the outer edge of the top A, and D' a similar molding on the outer edge of both sides B, these moldings being intersected at the junctions of said top and

sides by transverse moldings E. By these features I obtain a pillow-block possessing a neat and characteristic appearance.

What I claim as new, and desire to secure by Letters Patent, is—

1. The design for a pillow-block, consisting of the frame having the base C, the straight parallel sides B, rising therefrom, the arched top A, and the longitudinal moldings D D' D'' on the top and sides, respectively, substantially as shown.

2. The design for a pillow-block, consisting of a frame having an arched top and straight sides provided with longitudinal moldings on the outer edges, combined with transverse moldings which intersect the longitudinal moldings at the junctions of said top and sides, as shown and described.

In testimony whereof I have hereunto set my hand and seal in the presence of two subscribing witnesses.

FELIX BROWN. [L. S.]
